UNITED STATES PATENT OFFICE

OLIVER P. GREENSTREET, OF OWENSVILLE, MISSOURI

MOP WRINGER

Application filed October 13, 1928. Serial No. 312,349.

This invention relates to a mop wringer designed to be attached to a mop bucket and has for its primary object to provide an improved wringer device which may be used in association with any suitable bucket and which may be easily and quickly operated to grip the mop preparatory to squeezing or wringing the same.

The invention broadly contemplates the provision of a base carrying a frame comprising a pair of spaced upright members, between which the mop bucket may be positioned, and a transverse top member designed to carry a roller. Pivotally connected to the bar member at one end of the same is a vertically shiftable arm which normally extends in an upwardly inclined direction over the top member of the frame and which is designed to be swung downwardly to bring a roller carried thereby into contacting relation with a roller carried by the said top member. A spring normally maintains the vertically shiftable arm in raised position and attached to the free end of the arm is a foot operated lever by means of which the arm is drawn downwardly in the manner described.

A further object of the invention is to provide a mop wringer of the above described character which is of simple construction, strong and durable and inexpensive to manufacture.

The invention will be best understood from a consideration of the following detailed description taken in connection with the accompanying drawing forming a part of the present invention with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 is a view in side elevation of the mop wringer structure embodying the present invention;

Figure 2 is an enlarged side elevational view of the connected ends of the rollers;

Figure 3 is a sectional view through one side member of the frame showing the manner in which the foot lever is attached thereto;

Figure 4 is a plan view of a modified arrangement of the mop squeezing rollers.

Referring to the drawing in detail wherein like numerals of reference indicate corresponding parts throughout the several views, the numeral 1 indicates the base of the present mop wringer device, which base may comprise a metal frame or disc of wood or similar material. At diametrically opposed points the base 1 carries the upright bars 2 and 3, the upper ends of which bars are connected by a fixed cross arm 4. When a mop bucket such as that shown in dotted lines and indicated by the numeral 5, is in position upon the base 1 the fixed arm 4 will extend over the open top thereof.

At one end the stationary bar 4 is turned upwardly as indicated at 6 and terminates in a hinge knuckle 7. Secured to this hinge knuckle by a suitable pin 8 is a similarly formed end of a shiftable arm 9. The arm 9 overlies the fixed bar 4 of the frame and carries a roller 10 which extends substantially the entire length of the arm, this roller coacting with a similar roller 11 rotatably mounted upon the bar 4.

A suitable coil spring 12 is mounted upon the hinge knuckle 7, one end of this spring being attached to the shiftable arm 9 while the other end is secured to the fixed arm 4 or to the adjacent upright arm 3 of the frame, the spring acting to normally maintain the upper roller arm 9 in the raised position shown.

At its outer end the upper or shiftable arm 9 has a ring 13 formed for connection with the upper end of a pull rod 14. The pull rod 14 is mounted in vertical position adjacent the upright bar 2 of the frame in the guide eyes 15, these guide eyes being carried by the bar 2 as shown. The lower end of the pull bar is extended laterally to provide a foot piece 16.

The lower end of the bar 3 has secured thereto an outwardly extending pedal 17 upon which one foot of the operator is placed to

hold the frame and bucket stationary while the other foot is used to depress the pedal 16 of the bar 14 to pull the shiftable arm 9 downwardly during the mop squeezing operation.

5 While an ordinary conventional type of spring 12 has been shown for maintaining the roller 10 raised it is, of course, to be understood that I do not wish to be limited to this particular type of spring for it is obvious 10 any number of different designs may be employed without departing from the spirit of the invention. Any suitable metal may also be employed for constructing this control spring. In Figure 4 there is shown a slight 15 modification of the roller arrangement shown in Figures 1 and 2. In this modified form the end of the shaft 4^a which is fixed horizontally on the frame is formed to provide a laterally extending hinge sleeve 7^a through which a 20 suitable pivot bolt 7^b is passed.

The shiftable bar 9^a is formed at one end to provide a sleeve 9^b designed to position upon the bolt 7^b and operate against the sleeve 7^a which forms a part of the fixed bar. The 25 other end of this bar 9^a may be connected with a pull rod which, while not shown in Figure 4, may be mounted in the same manner as the pull rod 14 shown in Figure 1 so that upon application of the foot of the user 30 of the device to the lateral extension of the pull rod the roller 10^a may be swung down to a horizontal position at one side of the fixed normally horizontal roll 11^a to grip a mop placed between the rolls.

35 The roller 10^a of this modified structure may be caused to assume a raised position with respect to the fixed roller 11^a by the use of a spring device (not shown) similar to the spring used in connection with the preferred form.

40 From the foregoing description it will be readily seen that when the present mop wringer device is in use, ample room is provided for inserting the mop into the bucket 45 on either side of the wringer rolls and when it is desired to squeeze or wring out the mop it is positioned between the rolls and the same are drawn together in the manner described to grip the mop therebetween after 50 which the mop can be forcibly drawn from between the rolls which action will result in its being thoroughly squeezed out. Upon release of the pedal 16 the spring 12 will operate to raise the upper roller and its supporting arm 9 free of the lower roller preparatory to the introduction of the mop for 55 a second wringing operation.

Having thus described my invention what I claim is:—

60 1. A mop wringer of the character described comprising a bucket receiving frame, a substantially horizontal squeezing unit carried by the frame, a shiftable squeezing unit pivotally attached at one end to the frame 65 and designed to be brought into coacting re-

lation with the first mentioned unit for the performance of a mop squeezing operation, and a reciprocable foot operator carried by the frame and connected with the shiftable unit.

70 2. A mop wringer of the character described comprising a frame designed to receive a mop bucket, a fixed substantially horizontal roller carried by said frame to overlie the bucket, a shiftable roller pivotally attached at one end to the frame for up and down movement relative to the first mentioned roller for coaction therewith, means normally actuating said shiftable roller in one direction, and a vertically reciprocating 75 bar slidably attached to said frame and having one end connected to the shiftable roller, said bar being designed to be foot operated.

80 3. A mop wringer of the character described comprising a frame designed to receive a mop bucket including a base and a pair of uprights carried thereby, a fixed substantially horizontal roller supported by said uprights to overlie the bucket, a shiftable roller pivotally attached at one end to one of the uprights for up and down movement relative to the first mentioned roller, and means for drawing the shiftable roller toward the fixed roller comprising a bar member arranged for vertical reciprocation adjacent an upright and having its upper end loosely connected to the free end of the shiftable 85 roller and its lower end formed to receive an operator's foot.

90 4. A mop wringer of the character described comprising a frame designed to receive a mop bucket including a base and a pair of uprights, a fixed substantially horizontal roller supported by said uprights to overlie the bucket, a shiftable roller pivotally attached at one end to one of the uprights for up and down movement toward and away from the first mentioned roller, and a resilient member connected to said shiftable roller and normally operating to maintain the same in raised position with respect to the fixed roller, and means for drawing said shiftable roller downwardly against the tension of said spring comprising an operating rod secured to and adapted to have longitudinal movement upon the upright adjacent the free end of the shiftable roller, a loose connection between the upper end of the rod and the free end of the shiftable roller, and a lateral extension at the lower end of the rod for the reception of an operator's foot.

In testimony whereof I hereunto affix my signature.

OLIVER P. GREENSTREET.
